UNITED STATES PATENT OFFICE.

EMANUEL TREUCHL, OF SHADYSIDE, OHIO.

ENVELOPE HOLDER.

Application filed April 14, 1927. Serial No. 183,787.

This invention relates to clamps, presses or holders and more particularly to types adapted to support envelopes while the same are being opened.

5 One of the objects of this invention is to provide means to accommodate a plurality of envelopes, simultaneously, of different sizes and shapes.

Another object is in the provision of a 10 novel clamping means and a device for the actuation thereof.

A still further aim is to provide means preventing the clamp from losing its grip, thus assuring positive engagement of the 15 envelopes.

These various objects together with others, which will become readily apparent as the detailed description proceeds, are attained by the novel construction, combination and 20 arrangement of parts, hereinafter fully explained and shown in the accompanying illustrations, forming a material component of this disclosure, and in which:—

Figure 1 is a top plan view of an envelope 25 holder, made in accordance with this invention.

Figure 2 is a side elevational view of the same, showing a plurality of envelopes, of 30 different sizes and shapes, engaged therein.

Figure 3 is an end view of the same.

Figure 4 is a perspective view of a pile of envelopes, as used with the holder.

Figure 5 is a rear view of an envelope, as sealed.

35 Figure 6 is a perspective view of the same, having its flaps opened and showing the opening means.

Figure 7 is a like view of the envelope 40 shown in Figure 5, illustrating the manner of opening the same.

In the drawing, the numeral 10 generally designates a flat, rectangular base plate having in its under surface, recesses 11 extending from its shorter ends almost to its center 45 and in its upper surface, narrower recesses 12 extending almost from its center, nearly to the outer ends of the first recesses.

Fixed in the base intermediate the inner 50 ends of the recesses is a block 13 to which is fixed a partition 14 extending above the base in the center thereof.

Slidable in the recesses 11 are blocks 15 having slotted heads 16, reaching through the recesses 12, engaging partitions 17, the 55 blocks 15 having flat springs 18 fixed thereto

to frictionally engage the inner walls of the recesses 11.

Thus a plurality of envelopes X—X' of different sizes may be placed on the base 10, intermediate the wall 14 and the sliding 60 partition 17.

Formed on the base 10, at its four corners, are forked brackets 19, in which are pivoted ratched toothed rack bars 20—20', connected on the shorter side of the base by tension 65 springs 21.

A plate 22 having short transverse slots 23 at its corners, is engaged over the bars 20—20', the inner edges of the slots engaging the teeth of the racks, as best seen in Figure 70 24, the plate being further provided with a central rectangular opening 24, through which extend the partitions 14 and 17.

Pivoted to the upper ends of the rack bars 20—20' are converging link levers 25—25', 75 the meeting, upper ends of which are rotatably mounted or the outer ends of a connecting rod 26 extending therebetween.

As shown in Figures 4 to 7 inclusively, the envelopes X having enclosures "y" are provided with a cord loop "z", tight fitting along the inside and outside of one of the short flap creases, the end of the cord being knotted at "z", outside of the envelope.

Thus, after the pack of envelopes have 85 been placed on the base 10, intermediate the partitions 14 and 17 and with the cords "z" in a line, the plate 22 is depressed on the envelopes until the inner edges of the slots 23 engage the lowest possible tooth of the racks 90 20—20'.

The cords "z" are then pulled outwardly, obviously opening the envelopes without interfering with or defacing the enclosures "y".

After the envelopes have been opened, the 95 bar 26 is depressed, spreading the racks 20—20' against the action of the springs 21, permitting the plate 22 to rise and allowing removal of the opened envelopes.

Thus, it may be seen that a simple device 100 has been disclosed to effectively perform the intended purposes and while the preferred form has been described in detail, changes in construction may be made without departing from the scope of the appended claims.

Having thus described my invention, what I claim as new and desire to secure by Letters Patent, is:—

1. A press for envelopes comprising a base, a fixed partition on said base, a pair of slid-

2
able partitions in said base, pairs of racks pivoted on said base, tension springs connecting each of said pairs of racks, and means connecting said racks to urge the same outwardly against the action of said springs.

5 2. A press for envelopes comprising a base, a fixed partition on said base, a pair of slideable partitions in said base, pairs of racks pivoted on said base, tension springs con-

necting each of said pairs of racks, a plate 10 having slots engageable with said racks, converging levers pivoted on said racks and compressible means intermediate said levers to disengage said plate from said racks.

15 In witness whereof I have affixed my signature.

EMANUEL TREUCHL.
